UNITED STATES PATENT OFFICE.

HERMAN IHLENBURG, OF PHILADELPHIA, PENNSYLVANIA, ASSIGNOR TO
DAVID WOLFE BRUCE, OF NEW YORK, N. Y.

DESIGN FOR A FONT OF PRINTING-TYPE.

SPECIFICATION forming part of Design No. 12,636, dated December 27, 1881.

Application filed November 17, 1881. Term of patent 14 years.

To all whom it may concern:

Be it known that I, HERMAN IHLENBURG, (assignor to DAVID WOLFE BRUCE,) of the city and county of Philadelphia, Pennsylvania, have invented and produced a new and original Design for a Font of Printing-Type, of which the following is a specification.

The nature of my design is shown in the accompanying typographic impression, to which reference is made; and it consists of a heavy letter somewhat resembling the class known as "text," shaded on the right and below by a lighter line. The face of the letters is ornamented by the light dots, as shown, and in the

C, G, and S the terminations are rhomboidal-like. The up-and-down portions of the letters are concaved at top and bottom, as shown.

The character of the design is preserved in the punctuation-marks and the numerals and in the dollar and pound-sterling symbols. 20

Having now described my invention, what I claim as new is—

The design for a font of printing-type, as shown and described.

HERMAN IHLENBURG.

A. SIDNEY DOANE,
WILLIAM V. H. HICKS.
